CLOCK CASING

Siro R. Toffolon, Meriden, Conn., assignor to General Time Corporation, Stamford, Conn., a corporation of Delaware

Filed Dec. 23, 1968, Ser. No. 15,094

Term of patent 14 years

Int. Cl. D10—01

U.S. Cl. D42—7

FIG. 3

FIG. 2

FIG. 1

FIG. 4

FIG. 1 is a front elevational view of a clock casing showing my new design, the fragmentary cross-hatching within the frame indicating a material having the appearance of an open-weave fabric;

FIG. 2 is a top plan view;

FIG. 3 is a rear elevational view; and

FIG. 4 is a right side elevational view.

I claim:

The ornamental design for a clock casing, substantially as shown and described.
